Specification for Design.

Patented Sept. 22, 1914.

Application filed March 9, 1914. Serial No. 823,590. Term of patent 14 years.

To all whom it may concern:

Be it known that we, WINFIELD DEXTER SMITH and RUDOLPH J. BOURGEOIS, citizens of the United States of America, and residents of Chicago, in the county of Cook and State of Illinois, have invented a new, original, and ornamental Design for Dishes, of which the following is a specification, reference being had to the accompanying drawing, forming part thereof.

pot showing our new design. Fig. 2 is a plan view of the tea-pot.

We claim:

The ornamental design for a dish substantially as shown in the drawings.

WINFIELD DEXTER SMITH.
RUDOLPH J. BOURGEOIS.
